APPARATUS FOR STENCILING ARTICLES

Dietrich G. Rempel, Barberton, Ohio, assignor to
The Sun Rubber Company, Barberton, Ohio,
a corporation of Ohio

Application June 24, 1939, Serial No. 280,979

12 Claims. (Cl. 101—114)

This invention relates to apparatus for stenciling articles, such as character dolls, toys, or the like, and in particular relates to apparatus for stenciling such articles with paint spray.

Heretofore, it has been the practice to paint articles of the character described by first placing the article in a sectional stenciling mask, and then spraying paint through openings therein to stencil predetermined areas of the article. However, to prevent the paint from firmly adhering to the outer surface of the mask, it has been customary to coat the same with a suitable lubricant, so that an operator, in handling the registering sections of the mask and removing or replacing the article therein, frequently marked or soiled the article with grease, paint, or other substances adhering to his hands. Such soiled articles were either discarded or sold as seconds.

A purpose of this invention is to provide apparatus of the character described, in which an article may be positioned in or removed from the painting mask without marking or soiling the article.

Another purpose of the invention is to provide simple, efficient apparatus of the character described, in which articles may be spray-painted with maximum speed, and with a minimum amount of handling of the article-retaining mask by the operator.

These and other objects will be manifest from the following brief description and the accompanying drawings.

Of the accompanying drawings:

Figure 1 is a plan view, partly broken away, of the apparatus embodying the invention.

Figure 2 is a front elevation thereof.

Figure 3 is an enlarged detail, partly broken away and in section, taken substantially along the line 3—3 of Figure 1.

Figure 4 is the cross-section, partly broken away, taken on line 4—4 of Figure 3.

Referring to the drawings, the numeral 13 designates a work table supported on a frame 11 and having mounted thereon a U-shaped bracket 12 having spaced uprights 14 and 17 for supporting a rotatable work-holding shaft 13. Shaft 13 may be journaled at one end in an upright 14 of bracket 12, while adjacent its other end it may have integrally connected thereto an enlarged circular collar 15, which journals in a bore 16 extending through the other upright 17 of the bracket. An extension on one end of shaft 13 may be provided with suitable means, such as a crank-handle 18, for rotating the shaft in bracket

A substantial portion of shaft 13 at the opposite end from handle 18 may be longitudinally split or cut out at 13^b to provide an arm 13^a, the latter preferably having formed thereon a bifurcated head 20 for receiving shaft 13 at a point intermediate the uprights 14 and 17, and a pivot pin 21 being extended through head 20 and shaft 13 to permit arm 13^a to be swung to and from registry with the cut out portion 13^b of the shaft. Collar 15 may be radially slotted at 21 snugly to receive an integral cooperating flange 22 on arm 13^a to lock said arm against relative rotational movement on the shaft, the outer surface of flange 22 being arcuate to correspond to the bearing surface of collar 15 (see Figure 4). A slot 23, in upright 17, of slightly greater width than flange 22 or arm 13^a, may extend outwardly from bore 16, so that when shaft 13, carrying arm 13^a, is rotated to one position thereof with flange 22 in line with the slot, as shown in Figure 4, springs 24, 24, extended between the arm and outwardly extending brackets 25, 25 fixed on head 20, will yieldably urge arm 13^a outwardly through slot 23 to the chain-dotted position of the arm, shown in Figure 3. A curved plate 26, secured to upright 17 and having an upwardly extending slot 27 for receiving shaft 13 and arm 13^a, may be provided to limit the upward swing of arm 13^a by engagement with the upper end of the slot 27. In the open positions of arm 13^a, engagement of the latter with the sides of slot 27 prevents rotation of shaft 13 in its bearings in uprights 14 and 17 of bracket 12.

For clamping arm 13^a in registry with shaft 13 so that the shaft and the arm may be rotated as a unit in bracket 12, there may be provided outwardly adjacent support 17 a reciprocable U-shaped member or yoke 28, the curved upper end of which is of such radius as to engage about shaft 13 and arm 13^a to permit rotation of the same. Extending downwardly from yoke 28 may be a rod 29, the lower end of which connects a suitable foot-treadle 30 pivoted to a block 31 on the floor. This arrangement is such that downward pressure applied to treadle 30 will yieldingly urge arm 13^a through the aligned slots 23 and 21 and into engagement with shaft 13.

On the outwardly extending ends of the rod 13 and arm 13^a may be fixed a pair of blocks 32, 32 having slots 33, 33 therein for removably and replaceably receiving projecting bars 34 and 35 of a pair of registering sections 36 and 37, respectively, of a stenciling mask 38, sections 38 and 37 being secured in blocks 32 by means of thumb screws 33^a, 33^a. The mask 38 is of known type having

suitable shaped cavities therein for snugly receiving an article, such as a rubber character doll 39 or the like, and is provided with suitable openings 40, 40 of predetermined shape and size to permit penetration of spray to predetermined areas of the doll, as will subsequently be described.

The mask 38 is rotated, as required, to expose the various openings therein and a fine spray of paint is applied through these openings by means of a suitable pressure spray-gun 41, pressure-fluid being supplied to the gun, through piping 42, from a constant source of supply not shown. When gun 41 is not in use, it may be hung on a hook 43 on support 11.

Rearwardly and closely adjacent mask 38 is a hood 44, to which is connected a pipe 45 from a suitable suction means for carrying off excess paint spray.

20 In the operation of the apparatus the operator first rotates shaft 13 until arm 13^a is adjacent the open-ended slot 23, then he releases the pressure of his foot from treadle 39 to allow springs 24 to urge arm 13^a outwardly from the 25 full line position shown in Figures 1 to 4 to the chain-dotted position shown in Figure 3. While arm 13^a is in the latter position the operator removes the previously painted doll from the lower section 36, places it on a moving conveyor 46 at the rear of the painting apparatus, and inserts another doll to be painted. Next, by applying pressure on treadle 30 with his foot, arm 13^a is 30 swung inwardly on pivot 21 to bring the mask sections 36, 37 into registry, arm 13^a being yieldingly held in clamped position against the shaft 13 by the curved end of yoke 28. While the mask sections are thus held in registry, the operator may turn crank 18 with one hand, to rotate shaft 13 and arm 13^a as a unit. The spray gun 41 is 35 held in the other hand, substantially in the position shown in chain-dotted lines in Figure 2, and paint is sprayed through the various openings 40 in the mask, thereby applying coatings of paint to the portions of the doll 39 exposed through said 40 openings.

With the apparatus shown and described the operator can use one hand to operate the spray gun 41, while the other hand is kept clean for removing or replacing dolls in the mask 38, it being unnecessary for the operator at any time to handle the lubricant and paint covered sections 36 and 37 of the mask, to open or close the same.

It is understood that a number of units of the apparatus shown and described may be placed at a plurality of stations for performing various coloring operations on the same doll. However, several different colors may be applied at one station when the openings 40 of mask 38 are far 60 enough apart that spray applied to one opening will not reach another where a different color is required.

Modifications of the invention may be resorted to without departing from the spirit thereof or 65 the scope of the appended claims.

What is claimed is:

1. Apparatus for stenciling articles comprising, a unit including members movable toward and from each other, stenciling mask sections carried by the members and operable thereby to and from registering relation about an article to be stenciled, means for moving said members toward and from each other, means for rotatably mounting said unit, means for preventing rotation of 70 said unit when said sections are out of registry

with each other, and means for rotating said unit when the mask sections are together to expose various openings in the mask sections for reception of a spray of paint or the like through the mask openings. 5

2. Apparatus for stenciling articles comprising, a unit including members movable toward and from each other, stenciling mask sections carried by the members and operable thereby to and from registering relation about an article to be stenciled, means for rotatably mounting said unit, yieldable means on said unit for urging said members outwardly of each other to separate said mask sections when said unit is rotated to one position thereof, means operable at will to urge 10 said members inwardly to hold said mask sections in registering relation, and means for rotating said unit when the mask sections are together to expose various openings in the mask sections for reception of a spray of paint or the like through the mask openings. 15

3. Apparatus for stenciling articles comprising, a unit including a shaft and a member pivoted thereon, stenciling mask sections carried by said shaft and said member, said member being swingable from and toward said shaft to urge said sections to and from registering relation about an article to be stenciled, means for swinging said member toward and from said shaft, means for rotatably mounting said unit, and means for rotating said unit when the mask sections are together to expose various openings in the mask sections for reception of a spray of paint or the like through the openings. 25

4. Apparatus for stenciling articles comprising, a unit including a shaft and a member pivoted thereon, stenciling mask sections carried by said shaft and said member, said member being swingable from and toward said shaft to urge said sections to and from registering relation about an article to be stenciled, means for swinging said member toward and from said shaft, means for rotatably mounting said unit, means for preventing rotation of said unit when said member is swung outwardly on its pivot, and 30 means for rotating said unit when the mask sections are together to expose various openings in the mask sections for reception of a spray of paint or the like through the openings. 35

5. Apparatus for stenciling articles comprising, a unit including a shaft and a member pivoted thereon, stenciling mask sections carried by said shaft and said member, said member being swingable from and toward said shaft to urge said sections to and from registering relation 40 about an article to be stenciled, means for rotatably mounting said unit, yieldable means operable at will for swinging said member on its pivot to and from said shaft when said unit is rotated to one position thereof, and means for rotating 45 said unit when the mask sections are together to expose various openings in the mask sections for reception of a spray of paint or the like through the openings. 50

6. Apparatus for stenciling articles comprising, a unit including a shaft and a member pivoted thereon, stenciling mask sections carried by said shaft and said member, said member being swingable from and toward said shaft to urge said sections to and from registering relation 55 about an article to be stenciled, means for rotatably mounting said unit, yieldable means operable at will for swinging said member on its pivot to and from said shaft when said unit is rotated to one position thereof, means for preventing 60 rotation of said unit when the mask sections are together to expose various openings in the mask sections for reception of a spray of paint or the like through the openings. 65

venting rotation of said unit when said member is swung on its pivot, and means for rotating said unit when the mask sections are together to expose various openings in the mask sections for reception of a spray of paint or the like through the openings. 5

7. Apparatus for stenciling articles comprising, a unit including a rotatable member and an element pivoted thereon to swing toward and from 10 said member, stenciling mask sections carried by said member and said element and operable by swinging said element to move the sections to and from registering relation about an article to be stenciled, a plurality of uprights for rotatably 15 mounting said unit, yieldable means operable at will for swinging said element on its pivot when said unit is rotated to one position thereof in said uprights, at least one of said uprights having an opening therein to permit said element to be 20 swung therethrough in the last-named position of said unit, and means for rotating said unit when said mask sections are in registry to expose various openings in the mask sections for reception of a spray of paint or the like through 25 said mask openings.

8. Apparatus for stenciling articles, comprising a unit rotatable about an axis, said unit including members relatively movable toward and from each other substantially radially of said axis 30 and stenciling mask sections carried by the members to and from registering relation about an article to be stenciled, means for moving said members from and toward each other, and means for rotating said unit about said axis, said unit 35 thereby being rotatable about said axis to expose various openings in the mask sections for reception of a spray of paint onto an article received between the mask sections.

9. Apparatus for stenciling articles comprising 40 a unit rotatable about an axis, said unit including stenciling mask sections relatively shiftable substantially radially of said axis toward and from registering relation about an article to be stenciled, means for moving said mask sec-

tions from and toward each other, and means for rotating said unit about said axis, said unit thereby being rotatable about said axis to expose various openings in the mask sections for reception of a spray of paint onto an article received between the mask sections. 5

10. Apparatus for stenciling articles comprising a unit rotatable about an axis, said unit including stenciling mask sections relatively shiftable substantially radially of said axis toward 10 and from registering relation about an article to be stenciled, yieldable means for moving said mask sections from and toward each other, and means for rotating said unit about said axis, said unit thereby being rotatable about said axis to 15 expose various openings in the mask sections for reception of a spray of paint onto an article received between the mask sections.

11. Apparatus for stenciling articles comprising a unit rotatable about an axis, said unit including stenciling mask sections relatively shiftable substantially radially of said axis toward and from registering relation about an article to be stenciled, yieldable means for moving said mask sections from and toward each other, means for 20 rotating said unit about said axis said unit thereby being rotatable about said axis to expose various openings in the mask sections for reception of a spray of paint onto an article received between the mask sections, and, means for preventing rotation of said unit when said mask sections are moved from and toward each other. 25

12. Apparatus for stenciling articles comprising a unit including a pair of relatively shiftable registering mask sections having spray-receiving openings therein, means for supporting said unit at one side thereof, and means for relatively shifting said mask sections toward and from registering relation about an article to be stenciled, whereby paint or the like may be 30 sprayed through said openings to stencil an article received between the mask sections. 35

DIETRICH G. REMPEL.
